REAMER

Howard B. Book and Robert A. Hanlin, Oklahoma City, Okla., assignors to Reed Roller Bit Company, Oklahoma City, Okla., a corporation of Texas

Application April 1, 1939, Serial No. 265,394

5 Claims. (Cl. 255—73)

This invention relates to reamers for use in connection with drilling wells. It has for its general object the provision of a structure whereby reamer cutters of the roller type may be firmly and rigidly mounted within cutters recesses in a reamer body.

In mounting reamer cutters within their recesses it is essential that they be mounted as firmly as possible and that there be no possibility of play between any of the parts constituting the mounting during the operation of the reamer. It is, therefore, an object of this invention to provide a structure for mounting a reamer cutter in a recess in the side of a reamer body in such a manner as to give the greatest possible degree of rigidity to the mounting, prevent any play or lost motion between the parts of the mounting during operation, and at the same time use the smallest possible number of parts and eliminate any parts which might easily be broken or distorted.

A further object of this invention is to provide a structure for mounting reamer cutters in which the reamer cutter may be readily removed from and replaced in the reamer body without necessity for use of any special tools or skilled labor.

Another object of this invention is to provide a structure wherein the reamer cutter may be assembled upon its axle with means on the ends thereof for mounting the same in a reamer body, and this assembly inserted into or removed from the reamer body as a unit.

Another object of this invention is to avoid the necessity for delays and inconveniences resulting from breaking or wearing out of reamer cutters.

Other objects and advantages will become apparent from the following description taken in connection with the accompanying drawing, it being understood that the same is by way of illustration and example only.

In the drawing:

Fig. 1 is a side elevation of a reamer body constructed in accordance with this invention, showing the reamer cutters in place therein.

Fig. 2 is a vertical cross section through one wall of the reamer body illustrated in Fig. 1 and through one of the cutters mounted therein.

Fig. 3 is a horizontal cross section taken along the line 3—3 of Fig. 1 looking upwardly.

Fig. 4 is a side elevation of the sectional wedging ring securing device forming part of this invention.

Fig. 5 is a horizontal cross section taken along the line 5—5 of Fig. 1 looking upwardly.

Fig. 6 is a fragmentary horizontal cross section taken along the line 6—6 of Fig. 1.

Fig. 7 is a fragmentary vertical cross section 5 taken along the line 7—7 of Fig. 3.

In accordance with this invention, a reamer body 1 is formed with a major recess 2 and with auxiliary recesses 3 and 4 at the opposite ends of the major recess, respectively. It will be understood that while only one major recess and associated minor recesses are referred to in this description, there will be under ordinary circumstances two, three or even more major recesses with their associated reamer cutters in any given construction.

Welded to the opposite sides of each of the auxiliary recesses 3 at positions adjacent the ends of the respective major recesses there are provided wedge blocks 5, these blocks being tapered from end to end and from their exterior edge to their interior edge so that when secured in place by the welding indicated at 6 they will form tapering dovetail portions within each of the auxiliary recesses 3. These tapered dovetail portions are illustrated in the drawing as tapering toward a smaller dimension in a direction away from the major recesses 2.

About the body 1 and intersecting the auxiliary recesses 4 at the opposite end of each of the major recesses 2 there is formed a circumferential groove having side walls which converge inwardly toward the axis of the body and which groove is adapted to receive the sectional ring consisting of sections 7 and 8 which are hinged together by means of complementary hook-shaped portions 9 and 10 formed on their respective ends. The free end of the section 7 is bifurcated to form a pair of tongues or projections 11 and 12, while the free end of the other section 8 is formed with a tongue-like portion 13 of a width to fit between the tongues 11 and 12. Transversely through all three of these tongues 11, 12 and 13 there are provided openings adapted to receive a wedge-like member 14. This member 14 when forced into the transverse openings in the tongues 11, 12 and 13 will serve to draw the free ends of sections 7 and 8 toward each other and hold them together. This wedge member 14 is provided with a stem 15 projecting from its smaller end in alignment with the main body of the wedge 14 and threaded to receive a nut 16. The nut 16 is adapted to be seated within a recessed portion 17 in the side of the tongue 12 so that when it is tightened it will 55

draw the wedge 14 into tighter engagement with the sections 7 and 8 and draw these sections more tightly into engagement with the groove provided therefor.

5 As will be seen in Fig. 7, a small recess 18 is provided in the body 1 for the accommodation of the larger end of the wedge 14 and of a wrench for the purpose of turning the nut 16.

10 The reamer cutter 19 is rotatably mounted upon a cutter pin or shaft 20 having blocks 21 and 22, respectively, at its lower and upper ends. The block 21 at the lower end of the shaft 20 is illustrated as being made integral with the said shaft, whereas the block 22 at the upper end thereof is simply provided with an opening adapted to receive the upper end portion 23 of the shaft 20. This upper end portion is of slightly reduced diameter so that when the block 22 is placed thereon it will be definitely spaced from the block 21 by coming in contact with the shoulder 24 on the pin 20. This clearance will assure the proper space between the blocks 21 and 22 to accommodate the cutter 19. The block 21 is tapered toward a smaller dimension in a direction away from the reamer cutter 19 and in a direction outwardly with respect to the body 1 so that it will seat within the tapered dovetail portion of the auxiliary recess 3 and be held in place by the welded wedge shaped blocks 5.

20 The block 22 has an inclined portion 25 adapted to substantially register with one wall of the groove provided for the reception of the sectional hinged ring previously described when the cutter and blocks 21 and 22 are fully assembled with respect to the body 1. This block 22 also has a tongue-like part 26 projecting along the bottom of the auxiliary recess 4 and adapted to underlie the hinged sectional ring hereinabove referred to.

25 In assembling the parts, the body 1 is made up as at first described above and the blocks 5 are welded in place as shown at 6. The cutter assembly is also made up and prepared for mounting in the body. The cutter 19 is then placed about the pin 20 and allowed to drop into contact with the block 21 after which the smaller end of this block is inserted through the major recess into the upper end of the auxiliary recess 3. The block 21 is moved down in the auxiliary recess 3 until it wedgingly engages with said recess. The block 22 is now placed in the auxiliary recess 4 and moved downwardly over the end of the pin 20 to the position shown in Fig. 2. The sections 7 and 8 are hinged together as shown in Fig. 3 and placed about the body 1 over the tongue-like parts 26 and brought together until the tongues 11, 12 and 13 interlock with each other as shown in Figs. 4 and 7. The wedge 14 is inserted through the openings provided in the tongues 11, 12 and 13 and the nut 16 placed on the stem 15 and tightened to draw the wedge 14 into tight engagement with the sections 7 and 8, thus tending to reduce the size of the composite ring formed by these sections. This action, due to the inclination of the sides of the groove around the body and the corresponding cross sectional shape of the ring as shown in Fig. 4, will tend to urge the blocks 22 downwardly together with the shafts 20 and thus to seat the blocks 21 more firmly within the auxiliary recesses 3. At the same time, the composite ring referred to will assert a radial pressure against the inclined surface 25 of the edge of the blocks 22 and will ultimately come into contact with the tongue-shaped part 26 of each

of these blocks to hold them firmly in the auxiliary recesses 4 and prevent any radial outward movement of these blocks.

5 In the event it is desired to remove a worn cutter for the purpose of replacement or repair the reverse operation can be quickly carried out. It is only necessary to loosen the nut 16, drive out the wedge 14, remove the ring sections 7 and 8, lift out the block 22, and drive out the block 21. This can all be readily accomplished with- 10 out any special tools and without the necessity for any skilled adjustment. Likewise, no skilled adjustment is necessary when mounting the cutters in the body, it being necessary only to tighten up the respective securing means to the degree 15 desired.

10 It will be appreciated from the foregoing that the cutter assembly consisting of the roller cutter and the shaft and the end blocks may be assembled in the factory and extra assemblies 20 may be provided on each job at a relatively low cost. These assemblies may be removed and replaced as a unit in the manner above described, or if only one of the elements in the assembly be 25 worn or otherwise damaged, such element may be replaced without replacement of those not worn or damaged. The clearance for the cutters may be closely regulated by skilled operations in the factory so that the block 22 will always be spaced from the block 21 by the proper amount 30 to give the cutter the proper clearance.

25 Furthermore, when the cutter assembly is in place within the reamer body it will be found to be positively secured against movement in any direction and a rigid, trouble free mounting will be assured.

30 Having described our invention, we claim:

1. In a reamer construction, a reamer body having a major recess and an auxiliary recess at each end of said major recess, a reamer cutter shaft, a reamer cutter rotatably mounted thereon, a block carried by one end of said shaft and having a part adapted to wedgingly engage one of said auxiliary recesses, a block carried by the opposite end of said shaft and adapted to lie within said other auxiliary recess, a removable sectional ring adapted to be placed about said body and to overlie a portion of said second block and urge the same toward said first block, and means for removably securing said sectional ring 50 in place about said body.

2. In a reamer construction, a reamer body having a major recess and an auxiliary recess at one end of said major recess, a reamer cutter shaft, a reamer cutter rotatably mounted thereon, means forming a support for one end of said shaft adjacent one end of said major recess, and a block carried by the other end of said shaft and adapted to lie within said auxiliary recess, a removable sectional ring adapted to be placed about said body and to overlie a portion of said block to secure the same in said recess, and means for securing said sectional ring in place about said body.

3. In a reamer construction, a reamer body having a major recess and an auxiliary recess at one end of said major recess, a reamer cutter shaft, a reamer cutter rotatably mounted thereon, means for supporting one end of said shaft adjacent one end of said major recess, a block 70 on the opposite end of said shaft adapted to lie within said auxiliary recess, and a removable ring adapted to be placed about said body and to overlie a portion of said block to hold the same within said auxiliary recess, said ring compris- 75

ing two sections hingedly connected to each other at one pair of their adjacent ends, and means for drawing together the opposite pair of adjacent ends of said sections to tightly bind said ring about said body.

4. In a reamer construction, a reamer body having a major recess and an auxiliary recess at one end of said major recess, a reamer cutter shaft, a reamer cutter rotatably mounted thereon, means for supporting one end of said shaft adjacent one end of said major recess, a block on the opposite end of said shaft adapted to lie within said auxiliary recess, and a removable ring adapted to be placed about said body and to overlie a portion of said block to hold the same within said auxiliary recess, said ring comprising two sections hingedly connected to each other at one pair of their adjacent ends, said sections having overlapping parts on the opposite pair of their adjacent ends, and wedging means engaging said overlapping parts and adapted to draw the same together to decrease the size of said ring and bind it securely about said body.

5. In a reamer construction, a reamer body having a major recess and an auxiliary recess at each end of said major recess, one of said auxiliary recesses being in the form of a dovetail tapering toward a smaller dimension in a direction away from said major recess, a reamer cutter shaft, a reamer cutter rotatably mounted thereon, means on one end of said shaft having a part adapted to wedgingly engage said tapered dovetail, a block carried by the opposite end of said shaft and adapted to lie within said other auxiliary recess, a removable sectional ring adapted to be placed about said body and to overlie a portion of said second block and urge the same toward said first block as the size of said sectional ring is decreased, and means for decreasing the size of said opposite ring by drawing the sections thereof together into tight engagement with said body.
